UNITED STATES PATENT OFFICE.

GEORGE F. ATWOOD, OF NEWARK, NEW JERSEY, ASSIGNOR TO WESTERN ELECTRIC COMPANY, INCORPORATED, OF NEW YORK, N. Y., A CORPORATION OF NEW YORK.

WINDING-MACHINE.

1,381,899.

Specification of Letters Patent. Patented June 21, 1921.

Application filed December 6, 1918. Serial No. 265,618.

To all whom it may concern:

Be it known that I, GEORGE F. ATWOOD, a citizen of the United States, residing at Newark, in the county of Essex, State of New Jersey, have invented certain new and useful Improvements in Winding-Machines, of which the following is a full, clear, concise, and exact description.

This invention relates to a winding machine and more particularly to a serving head for spirally applying ribbon or tape to a continuous thread core. The invention will perhaps find its widest application in connection with machines for applying tinsel tape to a core to form an electrical conductor used in telephone switchboard cords and other similar compound electrical conductors.

The object of this invention is to provide a serving head for forming such tinsel conductors which may be operated at high speed without causing the frequent breakage of the tinsel tape which is incident to the operation of certain serving heads heretofore used when operated at high speeds.

In order to attain this object in accordance with one feature of the invention, means controlled independently of the centrifugal force developed by the rotation of the serving head is provided for maintaining a uniform tension on the tape, thereby eliminating breakage occasioned either by the spool from which the tape is fed, unwinding faster than is required, or by the drag of the spool when the head is started.

In accordance with this feature the frictional engagement of the braking means with the spool is controlled by the tension of the tape in such a manner that when the head is at rest, the pressure is greatest and decreases to a minimum when the machine is operated at its maximum speed.

In accordance with a related feature of the invention, the braking mechanism is so proportioned and arranged relative to the serving head that the effect of centrifugal forces, due to the rotation of the serving head at high speeds, is neutralized or reduced to a minimum.

These and other features of the invention, not specifically mentioned above, will more clearly appear from the following description and annexed drawing, in which Figure 1 is a perspective of a serving head constructed in accordance with the invention, and Fig.

2 is a perspective of a serving head having a slightly different arrangement of the braking mechanism. Similar reference characters are used throughout the various figures to designate similar parts.

In Fig. 1 of the drawings, 1 represents a hollow spindle or shaft suitably supported at 2, in bearings not shown, and driven at high speed by some suitable source of power. (Also not shown.) Extending longitudinally through the opening 3, in the shaft 1, is a thread core 4, delivered from a reel not shown, or other suitable means to the serving head and drawn therethrough at a definite rate of speed by other suitable means. (Not shown.) A light weight spool 6, from which the tape 7 is unwound, is loosely mounted on the spindle 1 by means of a sleeve having a flange 8.

Rigidly fastened to the collar 5, which is held in position on the spindle 1 by a set screw not shown, are diametrically opposite supporting arms 9 and 10. Coiled about the arm 9 is a spring 11, one end of which is attached to, and its tension regulated by, an adjustable nut 12. The other end of the spring 11 rests in a groove 13 in the flange 8, and acts as a brake to the movement of the spool 6 and the consequent unreeling of the tape 7. Rigidly mounted on the collar 5 and spaced substantially 90° from the arms 9 and 10, are the diametrically opposite arms 14 and 15, to which are pivoted at 16 and 17 levers 18 and 19, respectively. These latter mentioned levers are pivotally connected together at one end by a link bar 20, while the opposite ends thereof are equipped with tape guiding means consisting of grooved pulleys 21 and 22, respectively, the lever 18 is connected with the free end of spring 11 by a link 23, and stops 24 and 25 are provided to limit the outward movement of the levers 18 and 19.

When the serving head is in operation, the tape 7 is passed over the pulley 21 and then to the forward end of the spindle 1, where it is wrapped about the core 4 which is being fed through the head at a definite rate of speed. The arrangement of the lever 18 is such that when its forward end is drawn inward by the tension of the tape passing over the pulley 21, the other end is thrown outward, thereby through the medium of the link 23, decreasing the pressure of the spring brake 11 on the flange 8, 110

and consequently allowing freer rotation of the spool 6.

The lever 19 and pulley 22 which are duplicates of the lever 18 and the pulley 21 and which are similarly mounted, are provided for the purpose of centrifugally balancing the braking mechanism by counter-acting the outward movement of lever 18 caused by centrifugal force when the serving head is being revolved at high speed. This duplication of lever and pulley allows operation in either direction, if desired. Thus the free ends of both levers being thrown outward by the centrifugal force, no change in the pressure of the spring 11 on the flange 8 results.

Fig. 2 is a modification of the serving head shown in Fig. 1, from which it differs in that a single lever 26 having tape guiding pulleys 27 and 28, is used, which lever is pivoted to the supporting arm 29 at 30, the opposite end being counter-balanced by a weight 31 to compensate for the difference in length of the arms of the lever. It also differs in the arrangement of the brake, which consists of a spring 32 supported from the arm 33 by means of an adjustable collar 34 which may be secured in any desired position by means of a set screw 35. Connection between the lever 26 and the spring 32 is accomplished by means of a small bolt 36 which passes through a slot 37 in the spring 32 and is provided with two nuts for regulating the normal pressure of the brake on the periphery of flange 38 which forms a part of the sleeve on which the spool 6 is mounted. The weight of the lever mechanism carried by arm 29 is counter-balanced by a weight 39 carried by the arm 40 which is spaced substantially 180° from arm 29 on the collar 5, and arm 33 is counter-balanced by arm 41 which is spaced substantially 180° therefrom on the same collar 5. The tape guiding pulley 28 is provided so that the same head can be used for serving in a reverse direction, if desired.

In this arrangement of the brake operating means, centrifugal force is applied equally to each arm of the lever 26 by reason of the proper disposition of counter-balancing weight 31, and therefore no movement of the lever results, due to this force, to interfere with the operation of the brake caused by the varying tension of the tape when the serving head is in operation.

What is claimed is:

1. In a serving head, a spool for carrying the serving material, guiding means for

the serving material and a braking device 60 for the spool connected to and revolving with the serving head, said braking device being controlled by the guiding means independently of centrifugal force.

2. In a serving head, a spool for carrying 65 the serving material, a brake for the spool and centrifugally balanced means controlled by the serving material for automatically controlling the brake.

3. In a serving head, spool-carrying 70 means, a spool mounted thereon for carrying the serving material, a spring brake frictionally engaging the spool-carrying means and centrifugally balanced means for automatically controlling the pressure between the brake and the spool-carrying means.

4. In a serving head, a spool for carrying the serving material, means for retarding the feeding of the serving material 80 from the spool, and centrifugally balanced means responsive to the tension of the serving material for controlling the retarding means.

5. In a serving head, a spool for the serv- 85 ing material, a brake for controlling the spool, means controlled by the passage of the serving material to control the brake, and means for balancing the effect of centrifugal force on the brake controlling 90 means.

6. In a serving head, a rotatable spindle, a sleeve loosely mounted thereon, a spool mounted on the sleeve for carrying the serving material, a lever mounted on the spindle, a pulley mounted on one end of the lever for guiding the serving material, braking means for the sleeve controlled by the lever in response to the tension of the serving material passing over the pulley, and a second 100 lever pivotally connected to the first mentioned lever for balancing the effect of centrifugal force.

7. In a serving head, a rotatable spindle, a sleeve loosely mounted thereon, a spool 105 mounted on the sleeve for the serving material, a lever member mounted on the spindle, means mounted on the lever for guiding the serving material, braking means connected to the lever and controlled by the 110 tension of the serving material passing through the guiding means, and means for balancing the effect of centrifugal force upon the braking means.

In witness whereof I hereunto subscribe 115 my name this 5th day of December, A. D. 1918.

GEORGE F. ATWOOD.
